UNITED STATES PATENT OFFICE.

CALVIN A. WHITEHURST, OF BIRMINGHAM, ALABAMA, ASSIGNOR OF ONE-HALF TO
JOHN A. THOMPSON, OF NORTH BIRMINGHAM, ALABAMA.

DOOR LATCH.

Application filed August 6, 1926. Serial No. 127,655.

This invention relates to hardware and more particularly to an improved fastener for a swinging door.

One object of the invention is to provide a fastener comprising companion members adapted to be applied to doors hingedly mounted at the rear of a vehicle body and interlock to securely but releasably hold the doors shut.

Another object of the invention is to provide one member of the fastener with a latch which will be automatically moved into engagement with the other fastener member when the doors are closed and securely hold the doors shut until manually moved to a releasing position.

The invention is illustrated in the accompanying drawings, wherein

Figure 1 is a view in elevation showing the improved latch or fastener applied to swinging doors at the rear of a vehicle body;

Fig. 2 is an enlarged vertical sectional view taken on the line 2—2 of Fig. 1;

Fig. 3 is a transverse sectional view taken on the line 3—3 of Fig. 2;

Fig. 4 is a view similar to Fig. 1 with a modified form of latch or fastener applied to the doors;

Fig. 5 is an enlarged vertical sectional view taken on the line 5—5 of Fig. 4;

Fig. 6 is a transverse sectional view taken on the line 6—6 of Fig. 5.

The latch or fastener has been shown applied to doors 1 and 2 which are hingedly mounted, as shown at 3, and in the present illustration form closures for the rear end of a vehicle body, indicated in general by the numeral 4. While it is stated that the doors are employed to close the rear end of a vehicle body, it will be understood that they could represent closure doors for a garage or other building. It will also be obvious that instead of the companion members which form the latch or fastener being applied to companion doors one could be applied to a door and the other to a post or other stationary support.

The latch member, which is secured to the door 1 and is indicated in general by the numeral 5, consists of a metal bar 6 which is secured transversely of the door by screws or other suitable fasteners 7 and has one end portion 8 projecting from the free side edge of the door. This projected end por-

tion of the bar 6 is of less thickness than its inner end portion which is secured against the door and is provided with a side arm 9 having a longitudinally extending eye or slot 10 formed therein, as shown in Fig. 3. When the doors are closed, the projected end portion of the bar 6 extends transversely across the free side portion of the door 2 and beneath the companion latch or fastener member 11 which is secured thereon in transverse relation thereto.

The companion latch member 11 is also formed of metal and consists of a bracket having a base 12 from which extends an arm 13 formed with a longitudinally extending slot or eye 14. The bracket is secured against the outer face of the door 2 by screws or other suitable fasteners 15 and has its base portion provided with depending lugs or arms 16 which serve as abutments adapted to be engaged by the projected end portion 8 of the latch bar 6 so that the outer face of the door will not be marred and the arm 9 of the latch bar prevented from moving towards the door 2 beyond the proper position with respect to the arm 13, as shown in Fig. 2.

The latch plate 17, which serves to securely but releasably hold the latch member 5 in locked engagement with the latch member 11, is formed of metal and is pivotally mounted in the slot or eye 14 by a pivot pin 18 which passes transversely through the arm 13 adjacent the outer end of the slot 14. A recess 19 is provided in the outer upper corner portion of the latch plate and is adapted to receive the outer end portion of the arm 13 so that downward movement of the latch beyond the position shown in Fig. 2 will be prevented and upward movement in one direction also prevented. This latch plate is formed with a curved peripheral edge portion preferably constituting a segment of an ellipse, and from an inspection of Fig. 2 it will be readily seen that the inner or forward end of the latch plate terminates in slightly spaced relation to the inner end of the slot 14. The latch plate may be readily swung upwardly when the door 1 is closed and the outer end portion of the bar 6 engages the peripheral edge of the latch plate, but after the door is closed, the latch plate drops down into the slot 10 and as movement of the door in an opening direction cannot cause the plate to swing upward-

ly to a releasing position the two doors will be securely held closed. In order to release the doors and permit them to be opened, the latch plate must be swung upwardly until it moves out of the slot 10. In order to facilitate upward movement of the latch plate to a releasing position, there has been provided a prong 20 which extends upwardly above the arm 13 where it may be readily engaged by a finger of one hand. The intermediate portion of the latch plate is cut out, as shown at 21, to reduce its weight and permit a padlock or other suitable fastener to be engaged with its lower portion beneath the keeper and prevent the latch from being released by unauthorized persons.

In Figs. 4, 5 and 6, the latch bar 22, which corresponds to the bar 6, has one end fitting between the ear 23 and body portion of a bracket 24 and pivotally mounted through the medium of a rivet or other suitable fastener 25. By referring to Figs. 4 and 6, it will be seen that, when the bracket 24 is secured to the door 1 by screws or other suitable fasteners 26, the latch bar may be swung from the normal position shown in which it projects transversely from the door to an inoperative position. When in the operative position, the latch bar rests upon a supporting tongue or arm 27 which projects upwardly into overlapping relation to its outer face and serves not only as a stop or abutment to support the latch bar but also serves as a brace to prevent the latch bar from being bent or broken when it strikes the depending arms or lugs 28 carried by the bracket 29. The bracket 29 corresponds to the bracket 12 of the keeper 11 and carries an arm 30 which projects outwardly into overlying relation to the arm 31 of the latch bar 22 and is formed with an elongated eye or slot 32 with which the eye or slot 33 of the arm 31 registers, as shown in Fig. 5, when the doors are closed. A ring 34 is loosely supported in the eye or slot 32 upon a pin 35 extending transversely therein and is normally suspended in depending relation to the arm 30 so that it may fit into the eye 33 and securely hold the two arms interlocked and prevent opening of the doors. When the door 1 is swung closed, the latch ring may be swung upwardly towards the outer face of the door 2 and drops into the eye 33. It may not swing upwardly towards the outer end of the arm 30 a sufficient distance to release the latch bar and, therefore, the latch bar will be held in engagement with the keeper or bracket 29 until the ring is manually pushed upwardly through the eye 33 a sufficient distance to release the latch bar.

Having thus described the invention, I claim:

1. A fastener comprising a bar adapted to be secured to a movable closure with a

portion extending therefrom and formed with an elongated eye, a keeper including a bracket having a base adapted to be secured to a support and an elongated eye projecting from the base longitudinally of the eye of said bar and adapted to overlie the same when the closure is shut, and a latch plate pivoted in the eye of said bracket and normally having a portion extending beneath the same to fit into the eye of said bar, said latch being formed adjacent its pivot with a recess to receive the outer end portion of the bracket arm and prevent upward swinging of the latch in one direction.

2. A fastener comprising a bar adapted to be secured to a movable closure with a portion projecting therefrom and provided with a side arm formed with a longitudinally extending eye, a keeper including a bracket having a base adapted to be secured to a support and an arm extending from the base longitudinally above the arm of said bar and formed with a longitudinally extending eye, and a latch plate pivoted in the outer end portion of the eye of said bracket and extending longitudinally therein and of a depth to extend through the eye of said arm, the lower portion of said latch plate being formed with an arcuate edge and perforated to receive a fastener and the pivoted end portion being formed with a recess adapted to receive the outer end portion of the arm of said bracket to prevent upward movement of the latch plate in one direction to a releasing position.

3. A fastener comprising a member adapted to be secured to movable closure with a portion projecting therefrom and provided with a side arm formed with a longitudinally extending eye, a keeper adapted to be secured to a support and having an arm extending above the first-mentioned arm, and a latch pivoted to the arm of said keeper and extending below the same and of a depth to extend through the eye of the first-mentioned arm, the lower portion of said latch being formed with an arcuate edge and perforated to receive a fastener, the pivoted end portion of said latch being formed with an abutment adapted to engage the outer end portion of the keeper arm to prevent upward movement of the latch plate in one direction, said latch being adapted to be swung upwardly in an opposite direction to a releasing position.

4. A fastener comprising a bar adapted to be secured to a movable closure with a portion projecting therefrom and provided with a side arm formed with a longitudinally extending eye, a keeper including a bracket having a base adapted to be secured to a support and an arm extending from the base longitudinally above the arm of said bar and formed with a longitudinally ex-

tending eye, a latch plate pivoted in the outer end portion of the eye of said bracket and extending longitudinally therein and of a depth to extend through the eye of 5 said arm, the lower portion of said latch plate being formed with an arcuate edge and perforated to receive a fastener and the pivoted end portion being formed with a recess adapted to receive the outer end portion 10 of the arm of said bracket to prevent upward movement of the latch plate in one direction to a releasing position, and a prong extending upwardly from the latch plate above the arm of said bracket to facilitate 15 upward swinging of the latch plate in an opposite direction to a releasing position.

5. A fastener comprising a bracket

adapted to be secured upon a movable closure, a bar pivoted to said bracket and having a portion adapted to project from the 20 closure and provided with a side arm formed with a longitudinally extending eye, a lug extending from said bracket and adapted to engage beneath said bar to support the bar in a horizontal operative position, and a keeper including a bracket 25 adapted to be secured to a support and including an arm formed with an eye, and a latch pivoted in the eye of said keeper bracket and adapted to fit into the eye of 30 said bar.

In testimony whereof I affix my signature.

CALVIN A. WHITEHURST. [L. s.]
